FOLDING SCAFFOLD LADDER

Donald B. Fitzwater, 223 N. 13th St., Beatrice, Nebr.
Filed Mar. 6, 1959, Ser. No. 797,656
4 Claims. (Cl. 182—27)

This invention relates to folding scaffolds and more particularly it is an object of this invention to provide a folding scaffold which is adapted also to be used as an extension ladder and as a step ladder.

Heretofore various patents have been issued on devices which serve both as a scaffolding and as a ladder, an example is the patent issued to O. E. Lindfors, titled "Folding Ladder," Serial No. 801,388, issued October 10, 1905.

However, as distinguished from such devices, it is an object of this invention to provide a folding scaffold of an adjustable height and with the same components also providing both an extension ladder of a maximum rigidity and safety.

I achieve safety by using one section in a bridging relation with respect to the hinges of the other section.

I also provide rigidity with one of two overlapped sections arranged with its longitudinal members bearing against the longitudinal members of the other sections rather than against the rungs thereof. The latter has been used heretofore in the Austrian patent issued to Bosch, Patent 1,139,910.

A further object is to provide a four-section ladder in which the bridging or stiffening section, as described, can be used to extend downwardly from one of the other sections in order to make possible a scaffold of adjustable height.

Yet another object is to provide a scaffold in which two sections can be placed at an inclination with respect to the remainder of the ladder and in adjustable telescoping relationship with respect to each other in order to make one of the inclined sections extendible to make possible the positioning of a scaffold a greater or lesser distance from the side of a building.

A further object is to provide a scaffold in which the upper part is formed of hingedly connected sections arranged in triangle for more rigidly supporting horizontal scaffold boards, a part of the triangle being formed by a relatively strong section arranged at an acute angle with respect to the horizontal section for providing more rigidity whereby other means for providing such rigidity is unnecessary and the expense of the latter is avoided.

Other and further objects and advantages of the present invention will be apparent from the following detailed description, drawings and claims, the scope of the invention not being limited to the drawings themselves as the drawings are only for the purpose of illustrating a way in which the principles of this invention can be applied.

Other embodiments of the invention utilizing the same or equivalent principles may be used and structural changes may be made as desired by those skilled in the art without departing from the present invention and the purview of the appended claims.

In the drawings:

FIG. 1 is a side elevation of the ladder arranged in the position for providing a horizontal section spaced outwardly from the side of a building, the building being shown in dotted lines;

FIG. 2 is a side elevation of the ladder in position for providing horizontal section on which a workman can stand and on which the horizontal section is higher than in the view of FIG. 1;

FIG. 3 shows the ladder substantially in the same position as FIG. 2 but with the horizontal portion at a lesser distance from the bottom;

2

FIG. 4 is a view of the flights of the step ladder showing how the ladder is folded toward a storage position in which it is of compact size;

FIG. 5 shows a frontal elevation of a clip assembly of 5 the invention;

FIG. 6 shows a side elevation of the clip assembly of FIG. 5;

FIG. 7 shows the ladder in a position for storage;

FIG. 8 shows the ladder from a side elevation arranged 10 for use as an extension ladder;

FIG. 9 is a top plan view of the ladder in position of FIG. 8 when the ladder is laying horizontally, and as seen from the bottom of FIG. 8;

FIG. 10 is a view of the ladder in the position shown in 15 FIG. 8 and as seen from the top;

FIG. 11 particularly showing a pair of cleats attached thereto and for the purpose of engaging the rungs of other sections;

FIG. 12 is a side elevation of the ladder section of 20 FIG. 11;

FIG. 13 is a side elevation of the securing cleats of the present invention;

FIG. 14 is a side elevation of one of the hinges used to 25 secure the sections together;

FIG. 15 is a view of the ladder parts in position for 30 use as a step ladder;

FIG. 16 is a typical cross section through two of the flights of the ladder illustrating the cleats for retaining 35 the flights in assembled relation, and with part of one of the flights broken away.

Referring to the drawings and particularly to FIG. 8 it will be seen that the ladder of this invention comprises a first flight 40 having a secondly relatively short flight 12 connected thereto hingedly at one end of the first 35 flight.

The hinge connection is made by means of a hinge, best seen in detail in FIG. 14, the hinge being identified by the numeral 16 and having two parts 18 and 20 attached respectively to the first and second flights 40 and 12.

The hinge sections 18 and 20 have portions 22 which 40 extend outwardly to one side of each section respectively at those ends of the sections which are disposed adjacent each other.

The outwardly extending portions 22 of each pair of sections 18 and 20 of a hinge are connected together pivotally by a suitable pin 24 disposed on a side of the end sections 18 and 20.

As best seen in FIG. 9, each flight has a plurality of 45 equi-distantly spaced rungs 30 disposed between and connected to side rails 32.

The hinges 16 are connected to side rails 32 of the 50 respective flights 10, 12 and 40 with one hinge being disposed on the outer side of each side rail 32.

The second flight 12 is similarly composed of spaced rungs 30 and side rails 32.

Other hinges 16 connect the opposite end of the second 55 flight 12 to a third flight 10 which latter is also composed

60 of rungs 30 and side rails 32.

The first, second and third flights 40, 12 and 10 each have brackets or cleats 48 extending outwardly on one side thereof as best seen in FIG. 8, the brackets 48 being secured to the side rails 32 of the respective flights and 65 extending laterally and being L-shape with in-turned ends 49, best seen in FIG. 10, so as to receive thereunder a fourth flight 50 which latter is also composed of side rails 32 and rungs 30.

The fourth flight 50 is provided with a pair of securing 70 cleats attached thereto as shown at 60 in FIG. 11. The cleats 60 are elongated and are connected to the side

rails 32 of the fourth ladder section 50 by means of a pin 62 extending through a hole 64 in one end of the cleat.

The opposite end of each cleat 60 is provided with a protrusion 66 for engaging a ladder rung in a conventional manner. Each cleat is further provided with an arched slot 68 for receiving a pin 70 as extends also through the respective rail 32 as best seen in FIG. 11, the latter also being of conventional construction.

As best seen in FIG. 8, the fourth section 50 can be placed alongside the first, second and third sections and in position for overlapping the hinges between the other sections and with the cleat protrusions 66 engaging a selected one of the rungs of the first section 40. When in this position an extension ladder is formed for reaching a considerable height and the extension ladder will be rigid and safe.

Referring now to FIG. 4 it will be seen that the fourth section 50 can be placed opposite the first section 40 as they are preferably of the same length, thereupon the ladder can be folded as best seen by the arrow 72 in FIG. 4 whereby the first and second sections 40 and 12 respectively can be placed alongside the third section 10 to put the ladder in a compact, folded storage position, as best seen in FIG. 7.

Referring now to FIG. 15 we see in this view that the ladder is arranged for use as a step ladder in which the fourth section 50 is disposed alongside the third and second sections 10 and 12 which latter form two sides of a triangle having the first section 40 as the other side. A suitable safety chain 80 can be attached to the third section 10 and the first section 40 for keeping flights of the ladder in position.

Referring now to FIG. 1 it will be seen that when it is desired to arrange the ladder in the position for providing a horizontal section spaced outwardly from the side of a building 100, then the first section 40 is rested with its bottom on the ground 102 in a substantially upright position, the second flight 12 is arranged with its upper surface horizontal, and the third flight 10 is arranged in a position extending from its connection with the second flight 12 downwardly toward the first flight 40 at a substantial inclination with respect to the vertical, providing a diagonal brace.

Suitable means are provided for securing the first flight 40 to the third flight 10 at the lower end of the first flight whereby the first flight 40, the second flight 12, and the third flight 10 form a triangle with the first and third flights 40 and 10 disposed beneath and supporting the second flight 12. The preferred means for this is the clip shown in FIG. 6 which comprises two members 110 of substantially C-shape with their mid sections secured together by a bar 112 suitably attached to the mid section of each C-shaped member 110.

The endmost rung 30 of the terminal end of the third section 10 is received in corresponding hook ends 116 of the C-shaped members 110 and the hook ends 116 are fixed to the endmost rung 30 by means of pins 120 which close the respective hook ends of each C-shaped member 110.

As thus described it will be seen that the opposite ends 130 of the members 110 are adapted to hook about and engage the respective rung 30 of the first flight 40 which latter rung is selected in order to make the second flight 12 be disposed horizontally.

Referring to FIG. 1 it will be seen that the cross-section or flight 50 can then be placed on the underside of the third section 10 and lapping the first section 10 with the side rails of the fourth flight 50 being received in the brackets 48 of the first section 40.

As best seen in FIG. 1 the cleats 60 of the fourth flight 50 can be disposed in engagement with a selected one of the rungs of the third flight 10 in order to extend the upper end of the fourth flight 50 a desired distance to reach the wall 100.

Further, as seen in FIG. 1, the second flight 12 is spaced

outwardly from the building 100 in a position very handy for supporting a workman as he works on an outwardly projecting eave 120 of the building 100.

Referring now to FIG. 2 it will be seen that the fourth section 50 can be placed alongside of and overlapping the first section 40, and with the fourth section 50 disposed in the brackets of the first section 40 and extending downwardly beyond the third section 10 to elevate the second section 12 to a higher position, all other flights being in the same positions with respect to each other as in FIG. 1.

Referring to FIG. 3 an arrangement is shown which is the same as that described in FIG. 2 with the exception that the fourth section 50 is disposed co-extensive with the first section 40, as they are of the same length. Thus the fourth section 50 is not here used for extension but is in a storage position.

As thus described it will be seen that this invention has provided a ladder capable of use as an extension ladder, a step ladder, and further as a ladder for supporting one of its sections in horizontal position, either against or spaced from a building or the like.

From the foregoing description, it is thought to be obvious that a folding scaffold ladder constructed in accordance with my invention is particularly well adapted for use, by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice, except as claimed.

I claim:

1. In a folding scaffold and ladder, the combination which comprises a first ladder flight having spaced parallel side rails retained in spaced relation by spaced rungs, a second ladder flight having spaced side rails retained in spaced relation by spaced rungs, the length of the second flight being less than that of the first flight, hinges pivotally connecting one end of the second flight to an end of the first flight, a third ladder flight having spaced side rails retained in spaced relation by spaced rungs, hinges pivotally connecting said third flight to the end of the second flight opposite to the end of the second flight connected to the first flight, the length of said third flight being such that the combined length of the second and third flights is equal to that of the first flight, spaced cleats positioned on outer surfaces of the side rails of the flights and having L-shaped extended ends projected inwardly for retaining rails of one flight upon rails of another flight, means for anchoring the end of said third flight opposite to the end connected to the second flight to said first flight at a point substantially midway of the length of said flight, and a fourth ladder flight substantially of the same length as that of the first ladder flight and having spaced side rails retained in spaced relation by spaced rungs positioned with faces of the side rails thereof, selectively, in meeting relation with faces of the side rails of the second and third flights, or in meeting relation with faces of the side rails of said first flight; whereby the flights of the ladder may be, selectively, in nested relation for storage and shipping, or in extended positions with the upper portion of the first flight and second and third flights in extended relation forming a triangle, and wherein said fourth flight extends, selectively, from the upper end of the third flight, or from the lower end of the first flight.
2. A folding scaffold and ladder as described in claim 1, in which the means for anchoring the third flight on the first flight includes a bar having C-shaped members on the ends and wherein the C-shaped members are positioned to hook over rungs of the flights.
3. In a folding scaffold and ladder, the combination which comprises a first ladder flight having spaced paral-

70
75

lel side rails retained in spaced relation by spaced transverse rungs, a second ladder flight having spaced side rails retained in spaced relation by spaced transverse rungs, the length of the second flight being less than that of the first flight, hinges pivotally connecting one end of the second flight to an end of the first flight, a third ladder flight also having spaced side rails retained in spaced relation by spaced transverse rungs, hinges pivotally connecting said third flight to the end of the second flight opposite to the end connected to the first flight, the length of said third flight being such that the combined length of the second and third flights is equal to that of the first flight, and releasable means for anchoring that end of said third flight which is opposite to the end connected to the second flight to said first flight at a point substantially midway of the length of said first flight, whereby the flights of the ladder may be positioned, selectively, in an extended position with said second and third flights forming a triangle with the first flight upright and the second flight horizontal, or in a nested relation for storage and shipping with said second and third flights in alignment, and said first flight alongside and parallel to said third and second flights.

4. In a folding scaffold and ladder, the combination which comprises a first ladder flight having spaced parallel side rails retained in spaced relation by spaced transverse rungs, a second ladder flight having spaced side rails retained in spaced relation by spaced transverse rungs, the length of the second flight being less than that of the first flight, hinges pivotally connecting one end of the second flight to an end of the first flight, a third ladder flight also having spaced side rails retained in spaced relation by spaced transverse rungs, hinges pivotally connecting said third flight to the end of the second flight opposite to the end connected to the first flight, the length

5

10

15

20

25

30

35

of said third flight being such that the combined length of the second and third flights is equal to that of the first flight in a nested relation for storage and shipping with said second and third flights in alignment, and said first flight alongside and parallel to said first and second flights, spaced cleats positioned on the outer surfaces of the side rails of said first, second, and third flights and having L-shaped extended ends that project inwardly of said flights and generally parallel to said rungs, and a fourth ladder flight also having side rails retained in spaced relation by spaced transverse rungs, said fourth ladder flight being adapted to be received in selected ones of said cleats, whereby said flights are adapted to assume a nested relationship with said second and third flights in alignment and with said said first flight alongside and parallel to said second and third flights and with said fourth flight received in the cleats of said first flight or of said second and third flights.
